The ornamental design for a finger splint, as shown and described.

DESCRIPTION

FIG. 1 is a perspective view of a finger splint in accordance with the subject invention;

FIG. 2 is a perspective view identical to FIG. 1, however, including a finger in phantom illustrating the manner in which the finger splint may be used;

FIG. 3 is a top view of the finger splint illustrated in FIG. 1; FIG. 4 is an elevation view looking at the left hand side of FIG. 3;

FIG. 5 is elevation view looking at the right hand side of FIG. 3;

FIG. 6 is a bottom view of the finger splint;

FIG. 7 is an end view looking along arrows 7-7 in FIG. 3;

FIG. 8 is an end view looking along arrows 8-8 in FIG. 3;

FIG. 9 is a cross-sectional view taken along arrows 9-9 in FIG. 3;

FIG. 10 is a perspective view of the cross-sectional view illustrated in FIG. 9; and,

FIG. 11 is a perspective view showing the underside of the finger splint.

The broken line showing of a finger splint is for the purpose of illustrating portions of the article and forms no part of the claimed design. The broken line showing of a finger as seen in FIG. 2 is for the purpose of illustrating environmental structure that forms no part of the claimed design.
